UNITED STATES PATENT OFFICE.

JOSEPH W. ANTHONY, OF LYNN, MASSACHUSETTS.

LEATHER-FOLDING MACHINE.

1,326,828.

Specification of Letters Patent.

Patented Dec. 30, 1919.

Application filed March 16, 1917. Serial No. 155,845.

To all whom it may concern:

Be it known that I, JOSEPH W. ANTHONY, a citizen of the United States, residing at Lynn, in the county of Essex and State of Massachusetts, have invented an Improvement in Leather-Folding Machines, of which the following is a specification.

This invention relates to a machine for folding and creasing leather or similar material and is adapted for edge folding to complete the article manufactured in the machine described in my copending application, filed March 16, 1917, Serial No. 155,344. Certain features of my invention herein shown but not claimed are shown and claimed in my co-pending applications, Serial No. 79,205, filed Feb. 18, 1916, and Serial No. 155,343, filed March 16, 1917.

In the machine described and claimed in the said application the article to be manufactured included a facing section of material and an inner or reinforcing section. The machine is designed to fold three of the edges of the facing section onto the back or reinforcing section, to complete the article throughout at least three of its edges.

As in the specific article manufactured, it is necessary to subject the same to a further manufacturing detail before folding the fourth or final edge, a separate machine is necessary for such final edge folding.

The machine of the present invention is therefore constructed for folding the final or fourth edge of the article referred to, and in its specific construction involves a table on which the article, partly completed as described is clamped. A forming plate is carried by the clamp member, so that, in operative position, the said plate is projected beyond the edge of the clamp member to provide a section over which the machine in folding, through the movement of a wiper, turns said material onto the forming plate and, following the automatic withdrawal of the forming plate from the fold, presses the fold down into final position.

The details above noted are generally and more or less specifically characteristic of the several edge folding machines for which applications for patent are now pending in my name, and the present machine is designed particularly to provide a simple type of single edge folding machine, wherein the operations necessary to the edge folding,

are automatically carried out and controlled through a single slide member.

In the accompanying drawing

Figure 1 is a plan view of the improved machine.

Fig. 2 is a front elevation of the machine.

Fig. 3 is a transverse section of the same.

Fig. 4 is a section on line 4—4 of Fig. 2.

Fig. 5 is a sectional detail illustrating the bed lowering means.

Fig. 6 is an elevation of the operating slide.

Fig. 7 is a plan view of the same.

Figs. 8, 9, 10, 11 and 12 are sectional details illustrating the successive steps to which the article is subjected in the machine.

Fig. 13 is a rear face view of the article, the edge operated on by the present machine being shown in normal condition.

Fig. 14 is similar view of the article, the edge being folded.

The machine as illustrated in the accompanying drawings comprises a suitable base 1, above which, preferably at one end of the base is mounted a bed 2. The bed is arranged for movement to and from the base, being mounted upon guide rods 3, secured in the base, which guide rods are adapted to be engaged by an operating slide 4 to move the bed toward and from the base at proper intervals.

The slide 4 is mounted for reciprocating or oscillating movement longitudinally of the bed, being preferably arranged in a groove or channel 5 formed in the under side of the bed, and held against other than such movement in the bed by U-shaped sections 6 which underlie the slide and are removably secured to the bed. Supported on the base beyond the bed is a table 7, on which the material or article to be operated upon is to be clamped. The table is slidably supported for movement to and from the base by guide rods 8 depending from the table and extended through guide brackets 9 rising from the base, springs 10 encircling the rods, to maintain the upper surface of the table in alinement with the upper surface of the bed when the posts are in normal position. Adjustable screws 11 depending from the under side of the table serve to limit the downward movement of the table, rubber cushions 9' being provided on the brackets 9 for their engagement, collars 110

12 securing the rods 8 below the barring surface of the brackets 9, to limit the upward movement of the table.

A clamp frame 13 is arranged above the bed and slidably mounted for movement to and from the bed through rods 14 extending through the bed and into the base. The frame 13 is of open rectangular structure, in the front and rear frame bars of which 10 there is slidably mounted a resetting rod 15. The rod extends transversely of the frame, that is longitudinally of the base, and on the forward end beyond the frame the rod supports the clamp carrier 16. This carrier 15 is in the form of an elongated bar having a central upstanding ear 17 formed with an opening to receive the resetting rod, a set screw 18 fixing the carrier on the rod. The clamp frame is adapted for movement to 20 and from the table and the forward bar of such frame has secured to the lower portion thereof a clamp plate 19. The clamp plate is supported at its ends from the frame bar to provide a space between said clamp plate 25 and bar for the greater portion of the length of the plate, and on said plate, in the space thus provided, is arranged a forming plate 20 secured to the carrier 16. The forming plate is of such size with respect to the clamp 30 plate that at the inward limit of movement of the carrier with respect to the clamp frame, that is with the carrier in contact with the adjacent bar of the clamp frame, the operative edge of the forming plate will 35 be projected beyond the free edge of the clamp plate. At the limit of opposite movement of the carrier the forming plate is withdrawn so that its operative edge is approximately in line with the adjacent edge 40 of the clamp plate. The resetting bar 15 is normally held so as to maintain the forming plate in projected or operative position, by a spring 21 encircling the resetting bar and bearing between a bar of the clamp 45 frame and a shoulder formed by an enlarged head 22 on the end of the resetting bar. A pin 23 carrying a cam roll depends from the head 22 of the resetting bar into a position to be operated upon by the slide 4.

50 A wiper 24 is slidably mounted in an undercut recess arranged longitudinally of the bed, thus preventing other than a sliding movement of the wiper. The upper surface of the wiper is in a plane with the upper 55 surface of the bed, and the forward edge of the wiper is normally in alignment with that edge of the bed next to the table. The function of the wiper is to move laterally with respect to the table so as to form the edge 60 of the material by folding the projecting portion thereof over the forming plate, and the wiper is properly operated and timed through coöperation with the slide bar 4 through a pin 25, having a cam roll, depend-

ing from the wiper for coöperation with 65 slide bar.

The slide bar is reciprocated transverse the bed by a lever 26 pivotally mounted upon the base at 27 with its forward end formed with an elongated slot to receive a pin supported roll 28 depending from the slide bar, the engagement permitting a free vertical and longitudinal movement of the pin in the lever to prevent binding. The opposite end of the lever is moved to reciprocate the 70 slide bar through a cam groove 29 formed in a sleeve section 30 fixed on a driven shaft 31, here shown as actuated through gearing 32, from a belt driven drive shaft 33. The drive shaft has normally controlled clutch connection with a power means, as a belt pulley 33', to compel a complete reciprocation of the 75 slide bar at each operation of the clutch mechanism.

The slide bar is formed for the proper 85 timed operation of the various parts with what may be termed cam grooves. The initial operation of the machine, after placing the article upon the table 7 with its unfolded edge projecting slightly beyond the 90 rear edge of the table, is the downward movement of the carrier frame to cause the clamp plate 19 to clamp the article upon the table. To secure this result the inner or forward edge surface of the slide is formed with 95 a cam slot 34 having an initial or operating section 35 inclined downward, so that a pin 36 projecting from a cross bar 37 secured on the rods 14 of the clamp frame will by contact with the walls of said section of the cam 100 slot be given a downward movement to draw the clamp plate into contact with the article upon the table. The cam groove 34 has a second or holding section 36' substantially 105 parallel with the plane of movement of the slide so that for the length of time required for the travel of the pin through this section of the cam slot, that is while the edge is being formed about the forming plate by the wiper, the cam plate is held in clamp- 110 ing coöperation with the table. Beyond the holding section the cam groove 34 has an idle section 37', in which the groove is 115 without effect upon the clamp frame, such idle section being preferably widened vertically, to substantially free the clamp frame from further control for the succeeding folding action of the machine.

The upper surface of the slide 4 is formed with a cam slot 38 for the wiper and in 120 practically longitudinal alignment therewith is the cam slot 39 for the resetting bar. As the wiper does not go into action until the clamp frame has reached a position to 125 clamp the article upon the table, and to depress said table so that the upper surface thereof is substantially on a plane below the lower surface of the wiper, it is apparent

that the cam slot 38, which moves the wiper operating pin 25 must have an idle section 40 to permit movement of the pin therein, as the slide is moved, without affecting the 5 wiper. The cam slot 38 has an intermediate or operating section 41 inclining forwardly so that the wiper in the travel of the pin 25 through this section of the slot is caused to advance over the edge of the table and 10 so wipe or fold the projecting edge of the material over the forming plate as in Fig. 10. The cam slot 38 has a final or holding section 42 which extends in a plane substantially parallel with the plane of movement 15 of the slide, which through the pin 25 holds the wiper in its advanced or operative position. The resetting bar is operated through the slot 39, and as this slot resets the pin 23, and functions to withdraw 20 the forming plate from the fold following the initial folding operation of the wiper, it is apparent that the cam slot 39 has an initial idle section 43, and an intermediate operating section 44, arranged in 25 the form of an inclined wall portion to engage the pin, move the same in a direction against the pressure of the spring 21 to move the carrier 16 from the clamp frame to thereby withdraw the forming plate. As 30 the forming plate must be held withdrawn during the succeeding fixing of the fold the final section of the cam slot 39 is a holding section 45 in which the pin is so held as to maintain the folding plate withdrawn. 35 The idle section of the cam slot 39 is widened to permit free movement of the pin 23 in the return of the slide to normal position and avoid any action on said pin by the cam slot. Furthermore, the entrant 40 end of the idle portion 43 of the slot preferably has a downwardly inclined end wall 46 so that provision is made for the descending pin 23, making it unnecessary to provide a full length slot at its point. Following 45 the folding action of the wiper and the withdrawal of the forming plate, the fold rests between the wiper and table, and to fix the folded edge to the underlying material surface, assuming the folded edge to 50 have been previously cemented or otherwise coated with adhesive, it is necessary to add to the normal pressure between the wiper and table. This result is gained by compelling a downward movement of the bed 55 to similarly operate the wiper. This movement of the bed is had through cam slots 47 in the slide 4, to receive rollers 48 mounted on the ends of rods arranged transverse of the upper reduced ends of the 60 guide rods 3 on which the bed is slidably mounted. The cam slots 47 have an initial idle section 49 so that in the movement of the slide to effect the folding operations previously described the bed will not be 65 operated. The walls 47, however, have an operative section 50 so that at a proper time in the movement of the slide the bed will be depressed through coöperation with the rollers 48 with said operative portion of the cam slots. This depressed movement of the bed 70 forces downwardly the table 7, with the article, having a properly folded edge thereof, held between the wiper and table. The movement of the bed is such that it is continued slightly beyond the point at 75 which similar movement of the table is stopped by engagement of the screws 11 with the cushions 9'. This insures an independent and sufficient pressure of the wiper upon folded edge of the material as to insure a fixing of the folded portion in place. The table may be carried on springs sufficiently strong to avoid necessity of stopping movement of the table through the screws 11, and the fold receiving edge of the 80 table is or may be provided with a felt strip to aid in fixing the fold in place without a rigid surface resistance. 85

After the forming plate has been withdrawn from the folded edge of the material 90 it is important that it be prevented from running to projected or operative position until the parts have been returned to substantially normal or initial position. There is, therefore, provided a lock for holding 95 the carrier and hence the forming plate withdrawn. The lock is in the form of a locking bar 60, slidably mounted in the clamp plate frame and having an inner operative terminal 61 to engage an opening 62 in the head 22 of the resetting bar, this engagement being had out of the influence of a spring 63 encircling the locking bar and when the resetting bar has been operated by the cam action described to withdraw the 100 forming plate. The slide bar 4 is provided with a laterally extending pin 64 in the path of movement of which extends a depending end 65 of the locking rod. As the slide is returned to normal position the pin 105 64 engages and operates the locking bar to release the resetting bar, when the spring of the latter operates the carrier to project the forming plate to operative position. 110

As a further ornamentation of the article 115 it is desired that the face portion thereof be creased along the line of fold thus completing, in conjunction with the machine of the copending application, the edge crease of the article. An ordinary iron 51 is 120 mounted for this purpose upon the base, having its upper creasing edge 52 arranged to be engaged by the material immediately beyond the edge of the table and the wiper, the engagement taking place just prior to 125 the table reaching its final limit of movement. The increased pressure of the wiper will thus crease the surface of the material engaged by the iron. As noted in the previous applications for similar machines the 130

iron is of course to be heated, a heating means being indicated generally herein at 53.

The successive steps in the formation of the article, described above through the operation of the mechanism are illustrated in Figs. 8 to 12 inclusive. The article to be formed is shown in Figs. 13 and 14, Fig. 13 illustrating the article as delivered to the machine with what may be termed the rear edge open, while Fig. 14 illustrates the same article as completed by the machine, with said edge folded.

I claim:

1. A folding machine comprising material clamping means, a forming plate associated with said means, a wiper to coöperate with the forming plate to fold an edge of the material thereover, and a slide bar movable to successively operate the clamping means, 20 wiper and forming plate.

2. A folding machine comprising a base, a wiper, a bed mounted for movement toward and from the base, a table mounted for movement on the base, a clamping plate 25 to coöperate with the table to form a material clamping means, a forming plate associated with the clamping plate and movable with respect thereto, and a slide movable in the bed and operating to successively 30 actuate the clamping plate, the wiper and the forming plate.

3. A folding machine comprising a base, a wiper, a bed mounted for movement toward and from the base, a table mounted for movement on the base, a clamping plate 35 to coöperate with the table to form a material clamping means, a forming plate associated with the clamping plate and movable with respect thereto, and a slide movable in the bed and operating to successively 40 actuate the clamping plate, the wiper and the forming plate, and finally to depress the bed.

4. A folding machine comprising a base, 45 a wiper, a bed mounted for movement toward and from the base, a table mounted for movement on the base, a clamping plate to coöperate with the table to form a material clamping means, a forming plate associated 50 with the clamping plate and movable with respect thereto, a slide movable in the bed and operating to successively actuate the clamping plate, the wiper and the forming plate, means to lock the forming plate in 55 the position resulting from the operation of the slide in one direction, and means carried

by the slide to release the locking means in movement of the slide in the opposite direction.

5. A folding machine comprising a base, 60 a bed movable thereon, material clamping means arranged independent of the bed, a forming plate carried by the clamping means, a wiper arranged on the bed, and a slide movably supported in the bed, to successively operate in timed relation the clamping means, the forming plate, wiper and bed.

6. A folding machine comprising a base, a bed movable thereon, material clamping 70 means arranged independent of the bed, a forming plate carried by the clamping means, a wiper arranged on the bed, a slide movably supported in the bed, to successively operate in timed relation the clamping 75 means, the forming plate, wiper and bed, and a creasing iron coöoperating with the material following the operation of the bed.

7. A folding machine comprising a base, a bed movable thereon, material clamping 80 means arranged independent of the bed, a forming plate carried by the clamping means, a wiper arranged on the bed, a slide movably supported in the bed formed with cam-slots to engage, to successively operate 85 in timed relation the clamping means, the forming plate, wiper and bed, and a creasing iron coöperating with the material following the operation of the bed.

8. A folding machine including material 90 clamping means, fold defining means, folding means, a slide bar operable to operate said means, and locking means for said fold defining means.

9. A folding machine including material 95 clamping means, fold defining means, folding means and a reciprocating element associated with said means operable to control the operation of said means.

10. A folding machine including material 100 clamping means, fold defining means, material folding means, and a reciprocating element having cam surfaces engaging said means for the operation thereof.

In testimony whereof I have signed my 105 name to this specification in the presence of two subscribing witnesses.

JOSEPH W. ANTHONY.
